DOOR OPERATING MECHANISM

Edward F. Wagner, Lakeville, Ind., assignor to
The Studebaker Corporation, South Bend, Ind.,
a corporation of Delaware

Original application January 31, 1941, Serial No.
376,727. Divided and this application Decem-
ber 1, 1941, Serial No. 421,127

2 Claims. (Cl. 98—2)

This invention relates to door operating mechanisms and more particularly is concerned with a hinge or operating arrangement for doors in the side cowl of an automotive vehicle to be used as a ventilating means or as an entrance duct to an air heating or conditioning system for the interior of the vehicle.

This application is a division of my copending application, Serial No. 376,727, filed January 31, 1941.

One of the primary objects of the present invention is to provide an operating means which will insure positive opening and closing of the door from within the vehicle and will provide a predetermined opening in response to predetermined actuation of a control handle on the inside of the vehicle.

Another object of the present invention is to provide a construction which will be free of rattle and vibration and will positively hold the door in the desired position with the operator knowing at all times the position of the door with respect to the door opening.

In its broader aspects the present invention contemplates an operating handle having secured to it a disk carrying a pair of rollers which operate in a pair of symmetrical slots formed in an actuating bar whereby rotation of the handle produces predetermined movement of the actuating bar upon passage of the roller through the slots. The bar, in turn, has connected to it a hinge operating mechanism on which the door is supported whereby predetermined movement of the bar will result in producing a predetermined opening and closing movement of the door relative to the door opening.

In this connection means is provided for maintaining the actuating bar against rattling and predeterminedly positioning the rollers within the slots so that they will at all times move in the desired sequence. Further, resilient means is provided for moving the door towards closed position and for maintaining it closed against a suitable resilient weatherstripping mechanism which acts both as a cushion and sealing means.

Other objects and advantages of the present invention will appear more fully from the following detailed description which, taken in conjunction with the accompanying drawings, will disclose to those skilled in the art the particular construction and operation of a preferred form of the present invention.

In the drawings:

Figure 1 is an elevational view, with portions

broken away, showing the door operating mechanism and door mounting;

Figure 2 is a sectional view taken substantially on line 2—2 of Figure 1;

Figure 3 is a view corresponding to Figure 2 showing the door in a partially opened position;

Figure 4 is a detailed elevational view of the operating handle and actuating bar in door in closed position.

Figure 5 is a corresponding view of the mechanism in intermediate position; and

Figure 6 is a corresponding view showing the mechanism in full open position.

Referring now in detail to the drawings, a supporting plate 5 as shown in Figure 1 is secured at its corners to the inside panel 6 of the cowl of a vehicle or the like by means of the screws 7. Intermediate the upper and lower ends of the panel 5 there is provided a cross bar generally indicated at 8 which is also secured to the inside frame of the cowl by means of the screws 9. The cross bar 8 is preferably formed as a stamping and has the portion intermediate the ends thereof offset as shown clearly in Figure 2, and is pro-

vided with an aperture 10 adapted to receive the bushing 12 for supporting the operating handle. Secured by welding or the like to the inner face of the strap or bar 8 is the arm 13 which has a laterally offset portion 14 provided with a longitudinally extending slot 15. This places the portion 14 of the arm 13 inwardly between the outer panel 16 and the inner panel 6 of the cowl.

Screwed into the bushing 12 is a threaded sleeve 17 in which has been pressed and brazed the end 18 of a handle member 19 which projects outwardly through a rubber grommet 20 into the interior of the vehicle. The end of the handle member 18 projects beyond the inner end of the sleeve 17 and has brazed thereto a disk 22 which is also brazed to the end of the sleeve 17 thereby making a unitary construction in which the handle 19, sleeve 17 and disk 22 are assembled as a rigid unit.

The disk 22 has the rivet studs 23 spaced diametrically on opposite sides of the end 18 of the handle, which studs have enlarged collar portions 24 forming roller surfaces and head portions 25 for clamping the actuating bar 26 between the disk 22 and the heads 25. The actuating bar 26, at one end thereof, has inturned arm portions 27 forming means for supporting a vertically extending pin 28 beyond the ear portions 27. The end of the member 26 is provided with a stud 29 having a collar portion 30 slidable in the slot 15 of the arm 13 and provided with a head 31 whereby the bar 26 is held against lateral displacement.

relative to the portion 14 of the arm. Thus it will be seen that the bar 26 can move longitudinally with respect to the offset portion 14 of the arm by means of the collar 30 sliding in the slot 15.

Adjacent its opposite end the bar 26 is provided with a pair of semi-circular grooves or slots 32 and 33, respectively, which overlap each other so that one end of the slot 33, as indicated at 34, is disposed intermediate the ends 35 and 36 of the slot 32. These slots receive the collar portions 24 of the studs 23 whereby the rotation of the handle 19 will result in the collar 24 sliding along the slots 32 and 33 to move the actuating bar laterally from the door-closed position to door-open position. This movement is clearly illustrated in Figures 4 to 6, inclusive, which will be described in detail hereinafter.

The pin 28 carried by the arms 27 of the bar is adapted to pivotally secure one end of a rod 38 therebetween. Adjacent the opposite end of the rod 38 there is provided a transverse pin 39 and intermediate the ends of the rod a snap ring 40 is provided, acting as a seat for the washer 42 against which one end of the coil spring 43 is biased. The offset end of the spring is biased against a washer 44 and slides axially along the rod. Intermediate the washer 44 and the pin 39 the slotted end 46 of the arm 47 is disposed whereby the spring 43 normally tends to urge the end 46 of the arm toward the pin 39. The arm 47 has its angularly extending portion 48 secured against the face 49 of a bracket member which at its upper and lower ends is provided with in-turned ears 50 pivotally secured by pins 52 to the bracket 53 secured to the outer cowl plate. This mounts the arm 47 and the hinge member 49 for swinging movement about the pins 52.

Also secured against the opposite face of the portion 48 and arm 47 is a stamping 54 which is flanged for stiffening purposes and has the angularly offset flange portion 55 welded or otherwise secured to a door member 56 which door member is provided with peripheral inturned edges 57. The member 54, the arm 47 and intermediate portion 49 of the bracket 53 are all secured in firmly clamped relationship by means of a pair of studs 58 extending through and threaded into nuts 59 locked on the inner face of the bracket 49. This firmly clamps the entire assembly for unitary pivotal movement about the pins 52 so that the door 56 moves as a unit with the arm 47.

It will be noted that the outer plate member 16 which forms the panel for the cowl is recessed as indicated at 60 to provide a bracket for receiving the edge of the hood side plate member and at the opposite end the panel is provided with a recess 62 which receives the flanged edge of the conventional door. Intermediate the recesses 60 and 62 this panel is provided with a rectangularly shaped indented portion forming a rectangular channel 63. The channel 63 opens outwardly and defines the door opening. Secured within this channel is a strip of a soft resilient material such as rubber or the like, indicated at 64, which cooperates with the inturned edges 57 of the door to form a cushioning and sealing means therefor. The strip 64 may be cemented in position or otherwise retained in the channel.

Secured adjacent the forward recess 60 of the outerpanel is a plate member 65 welded or otherwise suitably secured to the cowl panel and having an extended portion 66 adapted to support

5 a screen member 67 in position. The screen extends substantially across the door opening and is for the purpose of preventing the entrance of dirt, insects or the like into the opening when the door is open. The screen, as will be apparent, is supported along one entire longitudinal edge and is sufficiently flexible so that it will not be damaged by the impingement of objects thereagainst.

10 Considering the Figures 3 to 6, the mechanism shown in Figure 3 indicates the door in its intermediate or half open position. This corresponds to the position of the actuating mechanism shown in Figure 5. Figure 2 illustrates the door in its closed position with the mechanism for moving the same positioned as shown in Figure 4.

15 Considering now the operation of the door mechanism, the details of this operation will be apparent from Figures 4 to 6. In Figure 4 the door mechanism is in door-closed position with the handle 19 in an upright position. Upon rotation of the handle 19 to the left, as viewed in Figure 4, the left-hand roller 24 moves downwardly in the slot 32 at the same time that the right-hand roller is moved upwardly and forwardly. Consequently, a translational movement of the bar 26 is effected and as the handle moves to a downwardly extending position as shown in Figure 5 the roller is moved entirely through the slot 32 from one end thereof to the other. This movement is accomplished by a 180° rotation of the handle member. At the same time the right-hand roller 24 has stayed within the end 34 of the slot 33 and has moved from one side of the roller adjacent the handle 19 to the opposite side thereof, thereby moving the bar 26 laterally to the left a distance equal to the distance between the rollers 24. The actuating bar 26 is restrained from separating movement by engagement of the rivet 29 in the slot 15 of the arm 13 and consequently the bar 26 moves laterally to the left, pulling the rod 38 therewith. Pulling of the rod 38 results in the cotter pin 39 at the free end thereof engaging against the formed end of the arm 37, producing a counterclockwise rotation of the arm and the brackets 50 and 54 about the pivots 52. This moves the door from the position shown in Figure 2 to that shown in Figure 3.

20 In order to prevent rattling of the actuating bar 26 and to hold the rollers positively in position in the ends of the slots, a spring 70, as shown in Figure 1, is connected to the actuating bar by being secured at one end in the opening 72 of the bar and at the other end to a bracket 73 secured to the inner panel 6 below the opening receiving the actuating mechanism. The lower bracket is provided with a flanged end 74 in which the opposite end of the spring 70 is retained. Consequently, there is a continuous downward tension on the bar 26 which maintains the rollers in proper position so that the bar 26 will move laterally upon rotation of the handle 19.

25 With the handle 19 in the position shown in Figure 5, that is, with the rollers 24 in the ends of the slots 32 and 33 as indicated at 34 and 36, further counterclockwise rotation of the handle, as viewed in Figure 5, results in the left-hand roller 24 of Figure 5 moving through the slot 33 to the end 37 of this slot, while the opposite roller 24 is retained in the end 36 of the slot 32 and produces the desired further movement of the actuating bar 26 to the left. Thus, in the full open position of the door as shown in Figure 6 the rollers 24 are in the opposite ends of the slots

32 and 33 from that position which they initially assumed when the door was closed as shown in Figure 4. The handle 19, at this time, has moved into an upright position corresponding to that of Figure 4 and the complete cycle of rotation has results in moving the actuating bar 26 laterally a distance equal to the distance between the ends of the slots, that is, a distance equal to the distance between the ends 35 and 36 or the ends 34 and 37. Reversal of rotation of the handle 19 from the position shown in Figure 6 moves the actuating bar 26 laterally to the right thus moving the rod 38 to the right and as clearly disclosed in Figures 2 and 3 the spring 43 then engages the opposite face of the arm 47 to force the door supporting bracket to swing in a clockwise direction about the pivots 62 toward a door-closed position. When the handle again assumes the position shown in Figure 4, the actuating bar 26 has moved through its full range of positions and consequently the door is restored to closed position as shown in Figure 2.

The use of the spring 70 is desired as it tends to maintain the rollers 24 in the ends of the slots and consequently gives an indication to the operator of the handle 19 as to the position of the door. The door will be firmly retained in any of the positions shown in Figures 4, 5 or 6 due to the tension of the spring 70 regardless of the effect of the wind on the door structure. Thus, a holding type of door opening mechanism is provided which is capable of indicating the position of the door in accordance with the position of the operating handle and which is rattleproof and free from vibration or the like so as to provide a sturdy, rugged construction of simple form.

It will be noted from Figures 1 and 4 that the end 35 of the slot 32 is slightly extended, whereby when the handle 19 is in door-closed position it is slightly cocked to the right, with the pins or rollers 24 out of alignment with a horizontal plane. This produces what might be considered an overcenter position as between the axis of the rod 38 and the left-hand roller 24. Thus the

handle, through the spring 70, is cocked against opening, and the spring 43 has full opportunity to function in holding the door closed, the pin 39 being out of the way, as shown in Figure 2. This holds the door against rattling and also imposes slightly greater resistance to initial door opening movement of the handle 19. It also serves as a means of indicating to the driver the position which the door occupies, since in full open position the handle is vertical.

I am aware that various changes may be made in certain details of the present construction and I therefore do not intend to be limited except as defined by the scope and spirit of the appended claims.

I claim:

1. In combination, a pair of spaced panels having substantially opposed openings, means for supporting said panels in fixed spaced relation with respect to each other to form a duct, a door for the opening in one of said panels, means for pivotally mounting said door adjacent an edge of the opening in said one panel, said last named means being disposed between said panels and accessible through the opening in the other panel, a door opening and closing mechanism disposed in the space between the opposed openings in said panels, said door opening and closing mechanism being adapted to be connected to said door through the opening in said other panel, and cover means for closing the opening in said other panel and supporting said door opening and closing mechanism.

2. The combination of claim 1 in which the door opening and closing mechanism comprises a rotatable handle mounted in the cover means for closing the open end of said other panel, an actuating member movable rectilinearly upon actuation of said handle, and a motion-transmitting rod movable substantially rectilinearly by said actuating member and connected to the pivotally mounted means for the door for opening and closing the same upon rotation of the handle.

EDWARD F. WAGNER.
